TAPERED-POLE-FACE GENERATOR

Clarence A. Atwell and Winston A. Brecht, Pittsburgh, Pa., assignors to Westinghouse Electric Corporation, East Pittsburgh, Pa., a corporation of Pennsylvania

Application November 20, 1947, Serial No. 787,204

4 Claims. (Cl. 171—228)

1

Our invention relates to direct-current generators which are used for loading internal-combustion engines, or other prime-movers, particularly those which are used for self-propelled cars and locomotives. Such generators have several special requirements, prominent among which is the ability to commutate successfully over a wide range of terminal volts and amperes.

More particularly, our invention relates to a type of power-plant using an electric generator which has a known type of excitation-system in which the main field amperes are sharply decreased as the load-amperes increase, thus causing the generator to drop its terminal-voltage sharply as the load-amperes increase. The low excitation of the main field at high-ampere loads means that the armature-reaction is very high, in comparison with the main-field ampere-turns, so that the main-field flux-form tends to be considerably distorted by the armature-reaction, that is, the flux tends to be greatly weakened under the leading pole-tip and strengthened under the trailing pole-tip. Of the known means for counteracting this distortion, the more commonly used curative means is a tapered main gap, which is so proportioned as to completely counteract the field-distorting effect of the armature-reaction at some chosen high-ampere load. This produces good commutation at high-ampere loads, but produces poor commutation at light-ampere loads, under which condition the tapered gap causes a main-field-form distortion in a direction opposite to that caused by the armature-reaction.

The object of our present invention is to overcome the above-mentioned difficulties by the simple, but novel, expedient of shortening the leading main-pole tip of such a machine, that is, of a direct-current generator having an air-gap which is tapered to counteract the distortion of the armature-reaction under high-ampere load-conditions accompanied by weak main-field excitation.

With the foregoing and other objects in view, our invention consists in the combinations, circuits, systems, machines, parts and methods of operation and assembly, hereinafter described and claimed, and illustrated in the accompanying drawing, wherein:

Fig. 1 is a curve-diagram illustrative of the general type of control which is needed on our generator;

Fig. 2 is a diagrammatic view of the generator, with a diagrammatically indicated control;

Fig. 3 is a partial sectional view of a ten-pole generator illustrative of our invention, with a con-

2

ventionally indicated commutator and brushes; and

Figs. 4 and 5 are, respectively, a developed end-view of two of the main poles and three of the commutating poles, and the corresponding field-form curve, of the generator shown in Figs. 2 and 3.

In Fig. 1, the curve 6 is a typical volt-ampere output-curve for the type of generator to which our invention relates, when said generator is running at full speed and receiving a certain fixed horse-power from the engine or prime-mover. In this curve, the portion 6'—6'' represents the constant-horse-power portion of the curve, and the operating-conditions of the generator. At load-amperes less than the value represented by the point 6', the generator is no longer capable of absorbing the given or constant output of the prime-mover. Such a volt-ampere characteristic requires high volts at low amperes, and low volts at high amperes, with the main field strongly excited at high volts, and with a weak main field at high load-amperes, as shown by the field-ampere curve 7 in Fig. 1.

Fig. 2 diagrammatically indicates such a generator, in which the generator-armature and commutator are symbolically indicated by a single circle G, the armature-current being delivered by brushes B₊ and B₋. The field-member of the generator is provided with main field-windings F and commutating-pole windings C. The commutating-pole windings C are connected in series with the armature-circuit, which is connected to the terminal load-leads L₁ and L₂. The main field-windings F are excited from a suitable diagrammatically indicated excitation-source E which is, or may be, responsive both to the terminal voltage of the generator and the load-current of the generator, the voltage response being symbolically indicated as being obtained by the connections 11 and 12 to the terminal leads L₁ and L₂, while the current-response is symbolically indicated as being obtained from the voltage-drop across the commutating windings C, by means of the connections 11 and 13. This is intended to be symbolically representative of the type of main-field excitation which is shown by the curve 7 in Fig. 1.

As more particularly shown in Figs. 3 and 4, the field-member of the generator G comprises a yoke 14 to which are attached ten main poles 15, and ten commutating poles 16. The main poles 15 have winding-receiving shank-portions 15' which are symmetrically spaced equidistantly from the commutating poles 16 on either side

thereof, this equidistant spacing being necessary in order to provide room for the main-pole and commutating-pole windings F and C, respectively, as indicated in Fig. 3. The main poles 15 have pole-face portions 15' which are characterized by leading and trailing pole-tips 17 and 18, respectively, which extend out in a circumferential direction on either side of each shank-portion 15'. As previously mentioned, the pole-face portions 15' are tapered at the air gap, so as to compensate for the distorting effect of the armature-reaction. The surface of the armature G is indicated, in Fig. 4, by the line 19. It will be noted that the leading pole tip 17 is spaced from the armature surface 19 by a smaller air gap than the trailing pole-tip 18.

In Fig. 5, the full-line field-form 21 shows the general shape of the resultant field-form at some specific high-ampere load, at which the field-distorting effect of the armature-reaction, which tends to weaken the main field at the leading pole-tips 17 and to strengthen it at the trailing pole-tips 18, is approximately exactly counteracted by the tapering of the pole-face air gaps of the main poles, resulting in a flat-topped field-form under each of the main poles.

Heretofore, the leading pole-tips 17 of generators of the type to which our invention relates have been shaped as shown in dotted lines at 17' in Fig. 4, so that the leading and trailing pole-tips were symmetrical with respect to the center-lines of the main poles, with the two tips extending the same circumferential distance on each side of the main pole 15. This had made the leading and trailing pole-tips 17' and 18 equidistantly spaced from the commutating poles 16 which are respectively adjacent thereto, as shown in Fig. 4.

In accordance with our invention, we space the leading pole-tips 17 by a greater circumferential distance from their adjacent commutating poles 16, than the corresponding spacing between the trailing pole-tips 18 and their adjacent commutating poles 16. In machines in which the available winding-space is so completely filled as to necessitate maintaining equidistant spacings between the shank-portion 15' of each main pole 15 and the two commutating poles in either side of it, so as to make room for the main-field and commutating windings F and C, the provision of an increased circumferential spacing between the leading pole-tips 17 and their adjacent commutating poles 16 is tantamount to a cutting off, or shortening, of the leading pole-tips 17, by an amount which is equal to the area between the dotted lines 17' and the full lines 17 in Fig. 4.

The effect of this shortening of the leading pole-tips 17, in accordance with our invention, is felt principally under operating-conditions in which the loading-ampères are low and the main field-strength is high, as shown in dotted lines in Fig. 5. Under these conditions, the armature-reaction has little distorting-effect, so that the tapered airgap causes a considerable field-form distortion, as shown by the dotted-line curve 22 in Fig. 5. In the old type of machine, in which the field-tips 17' and 18 were symmetrical as to their circumferential extents, there was a greater fringing of flux into the commutating zone from the leading pole-tip 17' than from the trailing tip 18, as shown at 23 in Fig. 4, and as shown by the portion b of the dotted-line curve 22 in Fig. 5. This was due to the shorter air gap in the leading tip, resulting in a shorter distance, in air, from the leading tip to the portion of the

armature-surface at the edge of the commutating zone; and this effect was considerably aggravated by the much greater flux-density at the leading pole-tip, as shown by the slanted shape of the dotted-line field-form curve 22 in Fig. 5.

In our invention, the leading pole-tip 17' is cut back to the point shown by full lines at 17, causing the corresponding fringing-flux of the field-flux curve to be moved back to the point shown at b in Fig. 5, so that the fringing of the main-pole flux from the leading tip 17 does not materially extend into the commutating zone at the surface of the armature. In this way, we have been enabled to obtain good commutation over the entire ampere-range of our generator, which was impossible before the pole-tip was changed.

While we have illustrated our invention in but a single form of embodiment, we wish it to be understood that our invention is susceptible of having various changes made, both as to the proportioning of the various parts, the substitution of equivalents, and the addition or omission of certain elements. It is desired, therefore, that the appended claims shall be accorded the broadest construction consistent with their language.

We claim as our invention:

1. A direct-current dynamo-electric machine having main poles and commutating poles, and windings on each set of poles, the main-pole faces being tapered along the air gap to compensate for the distorting effect of the armature-reaction for a given direction of rotation at some predetermined high-ampere load, the main-pole tip which is spaced by the smaller air gap from the armature being spaced further, from its adjacent commutating pole, than the spacing between the other main-pole tip from its adjacent commutating pole.

2. A direct-current generator having the ability to operate over a wide range of terminal volts and amperes, said generator having main poles and commutating poles, and windings on each set of poles, and means for energizing the main pole windings so that the generator operates at high volts at low amperes and low volts at high amperes, the main-pole faces being tapered along the air gap to compensate for the distorting effect of the armature-reaction for a given direction of rotation at some predetermined high-ampere load, the leading main-pole tip being spaced further, from its adjacent commutating pole, than the spacing between the trailing main-pole tip from its adjacent commutating pole.

3. A direct-current dynamo-electric machine having main poles and commutating poles, and windings on each set of poles, the main poles having winding-receiving shank-portions which are symmetrically spaced equidistantly from the commutating poles on either side thereof, the main-pole faces being tapered along the air gap to compensate for the distorting-effect of the armature-reaction for a given direction of rotation at some predetermined high-ampere load, the main-pole tip which is spaced by the smaller air gap from the armature having a shorter circumferential extent than the other main-pole tip, whereby the fringing of flux from the shorter main-pole tip into the commutating zone is substantially prevented under light-load conditions.

4. A direct-current generator having the ability to operate over a wide range of terminal volts and amperes, said generator having main poles and commutating poles, and windings on each set of poles, and means for energizing the main-pole

windings so that the generator operates at high volts at low amperes and low volts at high amperes, the main poles having winding-receiving shank-portions which are symmetrically spaced equidistantly from the commutating poles on either side thereof, the main-pole faces being tapered along the air gap to compensate for the distorting effect of the armature-reaction for a given direction of rotation at some predetermined high-ampere load, the leading main-pole tip having a shorter circumferential extent than the trailing main-pole tip, whereby the fringing of flux from the leading main-pole tip into the com-

mutating zone is substantially prevented under light-load conditions.
